METAL REINFORCED WOOD FLOOR

David A. Wallace, Detroit, Mich., and Lloyd E. Mendenhall, Partridge, Kans.; said Mendenhall assignor to said Wallace

Application March 20, 1936, Serial No. 69,842

12 Claims. (Cl. 20—8)

This invention relates to metal reinforced boards for building purposes, the reinforced boards being adapted for use in various types of construction wherein boarding is required and being particularly adapted for use in floors.

The primary object of the invention is to provide a board with a metal reinforcement to materially increase the mechanical strength thereof. The invention has particular utility in connection with floors inasmuch as the present boards may be mounted on spaced apart floor joists without the necessity of providing a subfloor or base therefor to support the boards on the spaced apart joists. Ordinary floor boards when secured to spaced apart floor joists are unsupported between the joists with the result that too great a degree of resiliency is present and this resiliency results in undesirable noises. In addition, the necessity for a high degree of mechanical strength makes it necessary to form the floor boards quite thick which is undesirable in hard wood floors for decorative as well as utilitarian purposes because such wood is expensive.

Another object of the present invention is to provide a wood floor which is fire-proof. In this connection the wood boards are reinforced by metal which is sufficiently strong to carry the loads to which the floor might be subjected so that in the event of fire a supporting surface remains even after the complete destruction of the wood floor.

Still another object of the invention is to provide a reinforcement for boards which tends to maintain the boards in a perfectly true condition, free from warps, so that the assembly of such boards into a building or floor structure may be made without the difficulty which ordinarily results in the assembly of boards which are warped.

Still another object of the present invention is to provide facing or flooring elements including metal parts with reinforcing characteristics and adapting the facing or flooring elements for direct attachment to a metal frame or building support by welding, so that such facing or flooring becomes an integral part of the building structure to function as a reinforcement therefor.

With the above and other ends in view the invention is more particularly pointed out with reference to the accompanying drawing, in which

Figure 1 is a section of an assembled floor;
Fig. 2 is a fragmental perspective of a board;

Fig. 3 is a fragmental perspective of a reinforcement;

Fig. 4 is a section of a floor illustrating a modified form of reinforcement;

Fig. 5 is a section illustrating a plurality of 5 boards in combination with a single reinforcement, and

Fig. 6 is a section illustrating the unit nailed to a wood support.

Like characters of reference are employed 10 throughout to designate corresponding parts.

Referring to Figs. 1, 2 and 3 the numeral 1 designates a board having lengthwise extending grooves 2 formed in the bottom surface, the plane of the grooves being obliquely disposed 15 with respect to the plane of the bottom of the board. The grooves 2 are preferably disposed in close proximity to the opposite sides of the board so as to be spaced a substantial distance apart. The numeral 3 generally designates a 20 metal reinforcement comprised of a web 4 formed with a series of lengthwise extending corrugations for reinforcement purposes as well as to provide for the reception of a bonding material as will hereinafter appear. The web portion 4 unites a pair of obliquely disposed tongues 5, spaced apart and corresponding in obliquity to the spacing and obliquity of the grooves 2 in the board 1. Projecting laterally from the tongues 5 are side flanges 6 and 7, the flange 6 25 being offset from the plane of the flange 7 so that the lower surface of the flange 6 is in direct alignment with the upper surface of the flange 7.

The board 1 is assembled on the reinforcement 35 3 by aligning the grooves with the tongues and sliding the board lengthwise onto the reinforcement. The contacting surfaces of the boards and reinforcement are coated with an adhesive which sets after the assembly operation and 40 firmly holds the parts together. The adhesive action is augmented by the friction between the tongues and grooves resulting from the tendency of the boards to warp while the tongues remain perfectly straight. The adhesive is indicated by 45 the relatively heavy lines 8 in Fig. 1 where it extends between adjacent boards and by the numeral 9 where it is disposed in the grooves between the corrugations in the webs 4. As illustrated in Fig. 1, when a plurality of boards are 50 arranged side by side on a support 10 such as a floor joist, the flanges 6 project into the spaces between the bottom surfaces of the boards and the flanges 7 on their respective reinforcements so as to provide a double tongue and groove in- 55

terlocking action. The adhesive 8 spaces the adjacent boards slightly apart and the use of an asphaltic adhesive is contemplated so as to provide a decorative effect by the presence of a black strip between adjacent boards. The reinforcements with the boards firmly attached thereto, may be secured to the supports 10 by nailing or by welding, as will hereinafter appear.

Referring to Fig. 4 the numeral 11 designates 10 boards secured to reinforcing members 12 by means of interlocking tongues and grooves as above described. In this form the web portions of the reinforcements are provided with corrugations of greater depth than those described in 15 connection with Figs. 1 to 3, and the flange 7a is bent back upon itself to provide a double thickness of metal at one side of each board. When the boards are assembled as shown side flanges 6a on the reinforcements interlock beneath the 20 flanges 7a. The boards 11 are secured to the reinforcements 12 by an adhesive 13 which might comprise an asphalt base as above described or may be shellac, mixed with wood powder or fine saw-dust.

25 The flanges 6a are provided with protuberances 14 which engage the metallic support 15 when the boards are assembled thereon, the protuberances being provided for projection welding purposes. The form shown in Figs. 1 to 3 may 30 be welded to the support 16 in like manner.

Fig. 5 illustrates the reinforcement of a plurality of boards by means of a single reinforcement, and also illustrates the use of conventional tongue and groove boards. In this view the numerals 16 and 17 designate boards having 35 interlocking tongues and grooves as designated at 18. The board 16 has an obliquely disposed groove 19 extending throughout the length thereof and board 17 has a groove 20 obliquely 40 disposed opposite to the groove 19. A reinforcing element having a corrugated base 21 has a pair of obliquely disposed tongues 22 extending throughout the length thereof. The two boards 16 and 17 are assembled with respect to the reinforcement with the tongues 22 extending into their respective grooves 19 and 20. An adhesive 23 is employed to increase the bond between the boards and the reinforcement.

Fig. 6 illustrates the present floor units secured to a support by means of nails. The boards 24 mounted on reinforcements 25 as above described are provided with countersunk bores 26 and the reinforcements with coinciding apertures 27. Nails 28 are driven through the bores 26 and apertures 27 and enter the support 29 obliquely. The boards are thus toe-nailed to the support.

Although specific embodiments of the invention have been illustrated and described it will 60 be understood that various changes may be made within the scope of the appended claims without departing from the spirit of the invention, and such changes are contemplated.

What we claim is:—

65 1. In combination, a strip shaped facing member, a metal reinforce, and means permanently securing said reinforce thereto, said reinforce having projecting side elements at each side thereof adapted to interlock one beneath another when said strips are laid side by side said reinforcements having their side projecting elements offset relative to each other such that opposite side elements of successive reinforcements successively overlie and underlie adjacent side elements

of adjacent reinforces when the strips are laid in place.

2. In combination, a wood board having grooves therein, and a metal reinforce having tongues received in said groove, said reinforce being formed of sheet metal and having corrugations providing alternating ribs and grooves for the reinforcement thereof, said ribs providing a seating surface for the board and the grooves being adapted for the reception of an adhesive. 10

3. In combination, a wood board and a metal reinforce, said reinforce being formed of sheet metal and having corrugations providing alternating ribs and grooves for the reinforcement thereof, said ribs providing a seating surface for 15 the board and the grooves being adapted for the reception of an adhesive.

4. In combination, a wood board, and a metal reinforce, means permanently securing said reinforce to said board, said reinforce having projecting side elements extending continuously throughout the length thereof and adapted to overlap one beneath another when a plurality of reinforced boards are laid in side by side relation. 25

5. In combination, a board having oblique grooves in a surface thereof, and a channel-shaped metal reinforce having spaced side walls united by an integral web, the side walls comprising oblique tongue portions and extending 30 into said grooves and securing the board to the reinforce.

6. In combination, a board having oblique grooves in a surface thereof, and a channel-shaped metal reinforce having spaced side walls 35 united by an integral web, the side walls comprising oblique tongue portions extending into said grooves and securing the board to the reinforce, said reinforce being provided with corrugated portions in the web thereof for the purpose of reinforcing the same and receiving an adhesive. 40

7. In combination, a board having spaced apart oblique grooves in a surface thereof, and a metal reinforce having spaced apart oblique 45 tongue portions extending into said grooves and securing the board to the reinforce, said reinforce having means projecting laterally therefrom and adapted to interlock one beneath another when a plurality of boards are laid side by side. 50

8. In combination, a pair of parallel boards, and a single metallic reinforce permanently secured to both boards, said reinforce having projecting means extending continuously throughout the length thereof and adapted to overlap one beneath another when a plurality of such pairs of boards are laid side by side. 55

9. In combination, a pair of boards, and a metallic reinforce secured to said boards, said reinforce having means adapted to interlock one with another when a plurality of such pairs of boards are laid side by side, and means uniting said interlocking portions, said last named means having corrugated portions providing for stiffening thereof and the reception of an adhesive material. 65

10. In combination, a pair of boards, each board having an oblique groove extending lengthwise parallel to the sides thereof, and a 70 metallic reinforce having a pair of obliquely projecting tongues and a web structure uniting said tongues, said web portion extending across the joint between the two boards and supporting said tongues extending into said grooves of 75

- respective boards and securing said reinforce and boards together.
11. In combination, a pair of boards, each board having an oblique groove extending lengthwise parallel to the sides thereof, and a metallic reinforce having a web extending across the joint between the boards and obliquely projecting tongues extending into said grooves, said web and tongues securing said reinforce and boards together, said reinforce having means adapted to interlock one with another when a plurality of reinforces are laid side by side.

12. In combination, a support, a board, a metal reinforce secured to said board, said reinforce having means adapted to interlock one with another when a plurality of boards are placed side by side on said support, said board and reinforce having coinciding means disposed with its axis oblique and spaced from said interlock means, and securing elements received in said means and extending into said support.
